US00D938974S

(12) **United States Design Patent** (10) **Patent No.:** **US D938,974 S**
Wang et al. (45) **Date of Patent:** **** Dec. 21, 2021**

(54) **DISPLAY SCREEN OR PORTION THEREOF WITH GRAPHICAL USER INTERFACE**

(71) Applicant: **Intuitive Surgical Operations, Inc.**, Sunnyvale, CA (US)

(72) Inventors: **Bai Wang**, Palo Alto, CA (US); **Scott S. Ichikawa**, Seattle, WA (US); **Aaron B. Tinling**, Chimacum, WA (US)

(73) Assignee: **INTUITIVE SURGICAL OPERATIONS, INC.**, Sunnyvale, CA (US)

(**) Term: **15 Years**

(21) Appl. No.: **29/667,213**

(22) Filed: **Oct. 19, 2018**

(57) **CLAIM**

The ornamental design for a display screen or portion thereof with graphical user interface, as shown and described.

DESCRIPTION

FIG. 1 is a front view of a display screen or portion thereof with graphical user interface showing our new design; and, FIG. 2 is another front view of the display screen or portion thereof with graphical user interface showing our new design.

The long-dash/short-dash/short-dash broken lines in FIGS. 1 and 2 illustrate a display screen and form no part of the claimed design.

The even broken lines in FIG. 1 illustrate portions of the graphical user interface and form no part of the claimed design.

1 Claim, 2 Drawing Sheets
